CENTRIFUGAL PUMP

Laurence Spence Sheldrick, Dearborn, Mich., assignor to Ford Motor Company, Dearborn, Mich., a corporation of Delaware

Application July 9, 1936, Serial No. 89,784

1 Claim. (Cl. 308—36.2)

The object of my invention is to provide a centrifugal pump especially adapted for internal-combustion engine. My improved pump is believed to be more efficient in operation and simpler to construct than the conventional type.

Still a further object of my invention is to provide a water pump which is lubricated by oil from the engine oiling system and which pump has provisions for keeping water which may seep through the pump seal from entering the oil reservoir. Heretofore most water pumps have been lubricated through grease fittings or a separate oil supply which requires periodic servicing. My improved construction requires no attention whatever as the oil reservoir is kept filled by the normal operation of the motor.

Still a further object of my invention is to provide a centrifugal pump having a single annulus of propeller vanes, and which pump is free from end thrust, due to the pressure developed on the fluid. In the ordinary pump which is inserted into a water jacket, the pressure developed by the pump is impressed upon the body of the impeller to produce end thrust. The applicant uses a thrust type of fluid pressure seal which functions correctly only with a small variation in load upon the seal and consequently, the elimination of end thrust allows a predetermined load to be applied with a spring or like means.

With these and other objects in view, my invention consists in the arrangement, construction and combination of the various parts of my improved device, as described in this specification, claimed in my claim and illustrated in the accompanying drawing, in which:

Figure 1 is a sectional view, taken vertically through my improved pump, and

Figure 2 is a sectional view, taken on the line 2—2 of Figure 1.

Referring to the accompanying drawing, I have used the reference numeral 10 to indicate the cylinder block casting of an internal-combustion engine, which casting has cylinder bores 14 formed therein in the conventional manner. The cylinder block is provided with a conventional water jacket which has a circular opening 11 extending therethrough over which my improved pump is mounted. An exhaust conduit 12 is cast into block 10.

The water pump comprises a housing 19 which is secured to the front wall of the engine by five cap screws 20. It will be noted from Figure 1 that the housing 19 is provided with a cylindrical sleeve 21 over which an inlet hose 22 is secured. This sleeve is aligned with the lowermost part 58 of the cylinder block water jacket and connects

with a vertically extending passageway 23 in the housing 19, which passageway 23 terminates in an opening 24 which is aligned with the opening 11 in the cylinder block. Thus water may enter through the sleeve 21 and then circulate upwardly through the passageway 23 and then through the aligned openings 24 and 11 so as to enter the cylinder block. It will be noted that a suitable flange 25 extends outwardly from the housing 19 through which three of the screws 20 are secured, while the other two screws extend through the center portion of each housing. Five cap screws are used to secure the housing 19 to the cylinder block in order that these housings may support the front end of the motor.

An oil reservoir 27 is cast integrally with the upper end of the pump housing 19, the reservoir 27 projecting forwardly therefrom and having a chamber therein in which oil is received. A bushing 28 is pressed through suitable openings in the walls of the reservoir and extends therethrough in substantial alignment with the opening 24. The bushing 28 is formed of porous bronze which is constructed so that lubricant applied to the outside of the bushing filters through and lubricates the shaft which is supported thereby. A pump shaft 29 is rotatably mounted in the bushing 28 and projects from each end of the bushing, the forward end of the shaft 29 having a pulley 30 fixed thereto. The other end of the shaft 29 is provided with an impeller 31, this impeller comprising a hub member having a radially extending flange 32 extending therefrom. It will be noted that the flange 32 is positioned inwardly through the opening 11 and that vanes 33 are cast integrally with the flange 32 so that water will be drawn in the conventional manner through the opening 24 and discharged radially by the vanes 33. A cylindrical sleeve 34 projects inwardly from the hub member of the impeller and drives a carbon disc 35 which forms the water seal for this pump. The disc 35 is resiliently urged against the end of the housing 19 by means of a spring 36. A suitable rubber water seal sleeve 37 coats with the shaft 29 and disc 35 to prevent water from leaking around the shaft. The water seal, per se, just described forms no part of this invention and is merely illustrated to show a suitable means of preventing water from leaking from the pump.

Referring to the drawing, it will be noted that a passageway 38 is provided between the outer wall of the housing 19 and the reservoir 27 through which the bushing 28 is pressed. The purpose of the passageway 38 is to allow water which may

leak between the inner end of the bushing 28 and the housing 19 to drain out of the pump and thus prevent such water from entering into the oil reservoir 27. Water that may leak or pass 5 the disc 35 and which travels along the shaft 29 will be thrown outwardly at the pulley end of the shaft to prevent its entering into the oil reservoir at this point. It will be noted from Figure 1 that an internal groove 53 is formed in the 10 periphery of the bushing receiving opening in the wall that separates the inlet and drain passageways. This groove allows the escape of fluid which may have leaked through the fluid seal, without requiring same to flow along the pump 15 shaft. Thus, the shaft may be lubricated along its full length without water tending to displace the oil.

Means will now be described whereby the oil reservoir 27 is kept filled with oil by the normal 20 action of the motor.

It will be noted that a cam shaft gear 39 is rotatably mounted within the engine in the conventional manner and that a cam shaft gear cover plate 40 is secured to the front wall 16 of the cylinder block to form a closure for the timing 25 gears of the motor. The casting 10 is provided with a passageway 42 which is aligned with the gear 39 and which extends toward the water pump propeller. This passageway terminates before reaching the water jacket and functions to 30 collect oil which may be thrown from the timing gear 39. A drilled hole 43 extends through a wall 16 which forms the front face of the casting 10 and communicates with the passageway 42. 35 A drilled opening 44 is machined in the pump housing 19 and extends from the reservoir 27 to position adjacent to the opening 43 so that the oil reservoir 27 is at all times in direct communication with the chamber in which the timing gear 39 is located. During the normal operation 40 of the engine, oil is thrown centrifugally by the

timing gear, some of which collects in the passageway 42 and flows through the openings 43 and 44 into the oil reservoir 27. The lubricant then filters through the bushing 28 to lubricate the shaft 29.

Some changes may be made in the arrangement, construction and combination of the various parts of my improved device without departing from the spirit of my invention, and it is my intention to cover by my claim such changes as may reasonably be included within the scope thereof.

I claim as my invention:

A fluid pump especially adapted for circulating cooling water through an internal-combustion engine comprising, a pump housing having a water 15 inlet passageway therein, which passageway terminates in an opening in said housing which is aligned with an opening in the water jacket of said engine, said pump housing also having an oil reservoir formed therein, and said housing 20 having a drain passageway disposed between said inlet opening and said oil reservoir, a bushing extending through said reservoir and drain passageway into said water inlet passageway, said bushing receiving oil from said reservoir, a pump 25 shaft rotatably mounted in said bushing having a driving pulley secured to its outer end and having an impeller secured to its inner end within said inlet passageway, said impeller forming an annular radial fluid seal with said pump housing, 30 and said housing having an internal groove formed therein which extends the length of said bushing receiving opening in the wall which separates said inlet passageway and said drain passageway, said internal groove conducting fluid 35 from between said annular seal and said shaft to said drain passageway, so that water which may leak through said annular seal may escape to said drain passageway without contacting said shaft.

LAURENCE SPENCE SHELDRICK.
